UNITED STATES PATENT OFFICE.

FRANCIS DANZENBAKER, OF WASHINGTON, DISTRICT OF COLUMBIA.

BEE-SMOKER.

No. 856,133.

Specification of Letters Patent.

Patented June 4, 1907.

Application filed March 14, 1904. Serial No. 198,055.

To all whom it may concern:

Be it known that I, FRANCIS DANZENBAKER, of Washington, in the District of Columbia, have invented a certain new and useful Improvement in Bee-Smokers; and I do hereby declare that the following is a full, clear and exact description thereof, reference being had to the accompanying drawings, in which—

10 Figure 1 is a perspective view of a bee-smoker constructed according to my invention; Fig. 2 is a vertical section of the same; Fig. 3 is a horizontal section through the fire cup on the line 3—3 of Fig. 2, and Fig. 4 is a detail view of a fragment of the fire-cup lining.

The object of my invention is to improve the construction of bee-smokers, whereby they will be simplified, their cost of manufacture cheapened, their efficiency increased, and they bettered in other respects, and to these ends my invention—consists in the smoker constructed substantially as hereinafter specified and claimed.

My smoker is of the type which comprises a cylindrical stove or fire cup and a bellows attached to the fire cup, at the side thereof, by which air is supplied, under pressure, both to maintain combustion in the fire cup and to cause the expulsion of smoke therefrom.

30 The stove or fire cup, A, consists of a simple or plain cylinder whose bottom is permanently closed and whose top has a removable lid or cover B, the fuel being accordingly placed in the fire cup through the top thereof. The lid or cover may be a simple cap adapted to be slipped on and off the top of the fire cup, but I preferably hinge or pivot it, employing for this purpose a strip of sheet metal C that is riveted to the lid or cover and 40 at one end is pivoted to the vertical extension d of the upper one of the brackets D that unite the fire cup and bellows.

Air enters the fire cup through a hole a at or near its vertical center, and it passes up and down therein through a vertical channel formed by a plate or partition E that extends from a point close to the bottom of the fire cup to a point nearly to the top thereof, the channel being closed at the top but open at 50 the bottom, so that air may emerge therefrom at the bottom of the fire cup to support combustion of material down to the very bottom of the fire cup, and thus assure the burning of all the material in the cup. At 55 points both above and below, but not in line with the opening a, the plate or partition E has

a number of small perforations e through which the air at various points, both above and below the opening a, may enter the fire cup from the channel. Because of the absence of openings through the plate or partition E opposite the opening a, it will be evident that air passing with force through such opening a and striking the imperforate portion of the plate or partition, will be deflected up and down the channel. I have no grate at the bottom of the fire cup, but the burning fuel rests directly upon the bottom of the cup, which consists of a piece of sheet metal and a sheet of asbestos paper, or the like, covering it to protect it from the heat. The bottom, it is to be observed, is supported a short distance above the bottom edge of the cup, so that when the latter stands upon a surface its bottom will not burn the same.

The plate or partition E has, at opposite edges, flanges e' that lie against the inner surface of the fire cup, and such flanges are attached to the fire cup, the same rivets being utilized to fasten them to the fire cup that unite the brackets D to the latter. The plate or partition is made of heavy sheet metal that it may withstand the heat.

To keep the fire cup cool, and thus increase its durability, as well as the comfort of handling the smoker, I preferably provide it with a lining of asbestos or other non-conductor of heat, which extends from the bottom to, or nearly to, the top of the cup. A very convenient way of applying this lining is to apply it in the form of a sheet a² to a circular or partly cylindrical shell a³ of sheet metal, whose edges are crimped or bent over the edges of the sheet of asbestos, the whole thing snugly fitting the fire cup and extending around in the same from one flange e' of the plate or partition E to the other flange thereof, as clearly shown in Fig. 3 of the drawings. Each of said flanges at its free edge is bent away from the wall of the fire cup to receive the edge of the lining. This lining device is not attached to the fire cup but is readily removable therefrom, so that it may be removed and renewed very readily when necessary.

The smoke exit is at the top, or near the top, of the fire cup, and consists preferably of a simple hole a' through the fire cup, without any nozzle in the form of a snout-like projection. The employment of a nozzle is objectionable, because it readily chokes up with soot and requires to be frequently cleaned

out, so that, by the elimination of the nozzle or snout, this is avoided. If desired, a smoke deflector may be employed above the smoke outlet or opening a' , which may consist of a simple, comparatively short, extension c of the hinge strip C of the cover, which extension overhangs the opening and is bent down at its opposite sides. Such extension, besides serving as a smoke deflector, is also useful in opening the lid or cover, as it may readily be knocked or bumped against any suitable object for this purpose. Preferably the edges of the exit or opening a' are turned outward a short distance, but neither this formation nor the employment of the deflector above the opening constitutes a nozzle for there is nothing of this nature employed, and there can be no collection or accumulation of soot in the structure I employ.

The rim or flange of the lid or cover may be so short that its lower edge comes merely to the level of the top of the opening a' , or it can be made of such length as to cause it to extend entirely over the opening a' , in which event it would be provided with an opening to register with the opening a' .

My bellows, as usual, consists of two boards F , connected together by a strip of leather G , one of the boards being movable toward and from the other to expel from and draw into the bellows, alternately, the air, a coil spring H being interposed between the two boards to move the movable one away from the other, but, of course, any other type of spring may be employed if preferred. Where I employ the coil spring, I secure its ends to the respective boards, which may be done by forming a point h on each end to enter the wood. The spring will thus be securely held in place against lateral movement, so that its power will always be exerted to the best advantage and the likelihood of its slipping sidewise and catching into the leather obviated, and it can be kept free from slack and under such tension as to utilize its energy to the best possible advantage. The air hole f in the stationary board of the bellows is directly opposite the air inlet a in the fire cup, and I employ no valve for such hole. It is to be remarked that back draft from the fire cup into the bellows is prevented by having the portion of the plate or partition E opposite the fire cup air-opening a imperforate. Preferably, I employ no thimble or sleeve between the bellows air hole and the inlet hole of the fire cup as, without the employment of such sleeve or thimble, an ample volume of air enters the fire cup, and there is an advantage in having some not enter it, but to strike and move along the sides of the fire cup, in that the latter is thereby cooled on the side that is next the hands in grasping the bellows; but, if preferred, such a sleeve or thimble may be employed, and one is indicated in dotted lines in Fig. 2 of the drawings.

I round or curve the corners of the bellows boards, as shown in the drawings, to avoid any sharp or angular bends of the leather that would cut or otherwise damage it, and, at the same time, I secure a more pleasing appearance of the bellows.

It will be seen that my smoker is a direct side and top burner, the air to support combustion passing into the channel formed by the side of the fire cup and the plate or partition E at its vertical center, and thence passing upward and downward and coming in contact with the burning fuel all along the side thereof, as well as entering it at the bottom of the fire cup, and thence passing upward through it to the top.

It will be seen that my smoker is extremely simple in construction; the fire cup has great fuel capacity; the smoker operates most efficiently, and it is convenient and comfortable to handle.

While I prefer the various details of construction which I have illustrated and described, it is to be understood that the scope of the invention is not limited thereto, as changes can be made which will involve no departure from the scope of my invention. Among other changes that may be made, I mention the employment of a differently constructed non-conducting lining for the fire cup, it being possible to use in place of that I have shown ribbed or corrugated paper of non-conducting material.

I do not claim herein the features of my bee-smoker wherein the smoke outlet has no snout; the strip to which the fire-cup lid or cover is attached, which projects over the smoke outlet; and the pivoting of the lid or cover to the bracket that connects the fire-cup and bellows, as claims thereto are in application No. 236,319, filed by me December 10, 1904.

Having thus described my invention, what I claim is:—

1. A bee-smoker comprising a fire cup having a channel, one side of which is formed by a perforated plate extending vertically through the cup, and having an air inlet that opens into said channel at the vertical center of the channel and means for forcing air into and through the smoker.

2. A bee-smoker, comprising a fire cup having a channel, one side of which is formed by a perforated plate extending vertically through the cup and having an air inlet that opens into said channel at the vertical center of the channel, and an air forcing device having an air outlet opposite said air inlet.

3. A bee-smoker, comprising a fire cup having a channel, one side of which is formed by a perforated plate extending vertically through the cup and having an air inlet that opens into said channel at the vertical center of the channel, and an air forcing device having an air outlet opposite said air inlet, said

plate being imperforate in line with said air inlet.

4. A bee-smoker comprising a cylindrical fire cup having a channel, one side of which is formed by a perforated plate extending vertically through the cup, and having an air inlet that opens into said channel, said plate having flanges on its opposite sides, and a lining for said fire cup that extends around the same from one flange to the other and means for forcing air into and through the smoker.

5. A bee-smoker comprising a fire cup having a channel, one side of which is formed by a perforated plate extending vertically through the cup, and having an air inlet that opens into said channel at the vertical center of the channel, and said channel opening at the bottom of the fire cup and means for forcing air into and through the smoker.

6. A bee-smoker comprising a cylindrical fire cup having a channel, one side of which is formed by a perforated plate extending vertically through the cup, and having an air inlet that opens into said channel, said plate having flanges on its opposite sides, and means for forcing air into and through the smoker and a lining for said fire cup that ex-

tends around the same from one flange to the other, said lining consisting of a sheet of non-conducting material and a sheet of metal whose edges are crimped upon the edges of the non-conducting material.

7. A bee-smoker comprising a fire cup having an air inlet, and a bellows having a single, constantly open passage for the inlet of air to the bellows and its exit to the fire cup.

8. A bee-smoker comprising a cylindrical fire cup, a channel at one side thereof, formed by a longitudinally extending plate and a portion of the fire cup, means for introducing air into said channel, a lining of combustible material for the bottom of the cup, and a removable lid or cover for the top of the cup.

9. A bee-smoker comprising a fire cup a removable lining therefor of non-conducting material and means for forcing air into and through the smoker.

In testimony that I claim the foregoing I have hereunto set my hand.

FRANCIS DANZENBAKER.
